COMB AND REED FOR TEXTILE MACHINES

Frank H. Kaufmann, Elkins Park, Pa., assignor to Steel Heddle Manufacturing Company, Philadelphia, Pa., a corporation of Pennsylvania

Application December 18, 1945, Serial No. 635,648

5 Claims. (Cl. 139—192)

1

This invention relates to combs and reeds for textile machines, and it relates more particularly to a novel construction and arrangement thereof.

In various kinds of textile machines there are employed combs and reeds for separating, guiding and manipulating the warp and weft threads. Such combs and reeds are used in various ways, in warping and leasing machines, and in looms for beating up the weft into the fell of the cloth. The reeds or combs at present in common use are usually made in two main types, in one of which the dents are held in proper spaced relationship on wooden strips at the top and bottom by means of pitch initially applied in a molten condition, and in the other of which the various parts of the reed are made of metal and said parts are secured to each other by means of solder or the like.

The present invention relates to that type of comb or reed in which the dents are spaced by being disposed in the successive convolutions of coil springs. In such structures bar members are usually provided on each side of the ends of the dents. Preferably there are also provided rods of chordal cross-section extending through the convolutions of the springs serving to position the same with respect to the side edges of the dents near the ends thereof. After the parts are assembled as aforesaid, the same are secured to each other by causing melted solder to flow into the interstices in and around the ends of the dents and in and around the spacing springs, which solder also serves to secure and hold the side bar members in place.

Heretofore, in the construction of combs or reeds of the character aforesaid, one of the principal difficulties has been to insure the proper disposition of the solder in the interstices in and around the ends of the dents and in and around the coil springs employed, without at the same time having the solder extend into the spaces between the dents where the same is not desired. Frequently, in the endeavor to prevent the solder from extending into the spaces between the dents, the spring would be left uncovered at certain points with the result that, in the use of the comb or reed, the warp would become caught or jammed with respect to the coils of the spring.

The principal object of the present invention is to provide a comb or reed of the soldered type in which fouling of the warp and weft threads with respect to the coils of the spring will be effectively prevented, particularly at such places

2

along the springs where the springs are not entirely covered or filled in by the solder.

A further object of the invention is to provide a comb or reed of the soldered type in which the various parts may be more readily and quickly assembled, and in which uniformity of the spacing of the dents will be assured.

The nature and characteristic features of the invention will be more readily understood from the following description, taken in connection with the accompanying drawing forming part hereof, in which:

Figure 1 is a front elevation of a comb or reed embodying the main features of the present invention;

Fig. 2 is an enlarged section thereof taken approximately on the line 2—2 of Fig. 1; and

Fig. 3 is a fragmentary perspective view illustrating the manner of assembly of the various parts, the solder in this case being omitted.

It should, of course, be understood that the description and drawing herein are illustrative merely, and that various changes and modifications may be made in the structure disclosed without departing from the spirit of the invention.

Referring to the drawing, the reed therein shown is in many respects similar to the ordinary types of soldered reeds, being provided with end struts 10 between which the dents 11 are located in spaced relationship. The dents 11 are preferably made of thin flat strips of metal.

The means for spacing the dents 11 comprises the provision, near the top and bottom of the frame of a coil spring 13. The end portions of the dents 11 are disposed in the successive convolutions of the spring 13. As in all of the arrangements of this general type, the dents 13 are inserted from one and the same side of the spring 13, so that a portion of each convolution of the spring 13 extends into one of the dent spaces, and then crosses over the front edge of the dent 11 into the next adjacent dent space. A rod 14, of chordal shape in cross-section, is inserted through the convolutions of the spacing spring 13 on the sides of the dents 11 over which the convolutions of the spring crosses, and these parts are so dimensioned and located that the periphery of each coil of the spring 13, on that side of the spring into which the ends of the dents 11 are initially inserted, is in alignment with the edges of the dents on that side thereof.

On that side of the dents 11 on which the rod 14 is inserted in the spring 13 there is mounted a bar 15 extending from end to end of the frame

and preferably of such width as to extend from the spring to the ends of the dents.

There is also provided a bar 16 secured to the opposite side edges of the dents 11 near the ends thereof. This bar 16 is of such dimensions that the inner marginal edge 17 thereof is disposed a slight distance beyond the innermost portions of the convolutions of the spacer spring 13 and the other edge of the bar 16 is preferably disposed in alignment with the ends of the dents 11.

After the various parts are assembled, the top and bottom portions of the frame are dipped in molten solder, which will serve to secure the parts to each other, and also fill out the interstices at the ends of the dents between the bars 15 and 16, and in and around the convolutions of the spacer spring 13. The solder is indicated at 18 in Fig. 2 of the drawing. The solder is not shown in Fig. 3 of the drawing for clarity of illustration.

By the foregoing arrangement there is provided a reed in which there will be no possibility of the warp threads passing through the dent spaces being caught in the convolutions of the spacer spring, even though the solder does not fully cover the coils at all parts, as the inner edge of the bar 16 is so positioned as to prevent the warp threads passing through the dent spaces from coming in contact with the coils of the spacer spring and becoming caught at these places.

Furthermore the arrangement is such that the assembly of the various parts is greatly facilitated. The inner surface of the bar 16 serves as an abutment against which the successive convolutions of the spring will contact when the parts are being assembled.

While the invention has been shown as applied to a reed of the type in which the dent spaces are closed at both the top and the bottom, nevertheless the same may be employed in other types of reeds and combs, as for example, those in which the dent spaces are open at the top to permit the ready insertion of the warp ends, and also in combs of the type in which the dents are provided with intermediately located hooks or obstructions for the purpose of effecting leasing and other manipulations of the warp.

I claim:

1. A metallic reed or comb for textile work having a plurality of spaced dents mounted therein, a coil spring for spacing said dents in the structure having its convolutions extending into the spaces between the dents from one face of the reed but not beyond the other face thereof, and a bar mounted on said other face and extending inwardly from the edge to beyond the spring.

2. A metallic reed or comb for textile work having a plurality of spaced dents mounted therein, a coil spring for spacing said dents in the structure having its convolutions extending into the spaces between the dents from one face of the reed but not beyond the other face thereof, a bar mounted on one face adjacent an edge of the structure and extending inwardly from said edge to a projecting portion of said spring, and a wider bar mounted on the other face and extending 65 inwardly from the edge to beyond the spring.

3. In a metallic reed or comb for textile work having a plurality of spaced dents mounted therein, a coil spring for spacing said dents in the structure having its convolutions extending into the spaces between the dents from one face of the reed but not beyond the other face thereof, a bar mounted on one face adjacent an edge of the structure and extending inwardly from said edge to a projecting portion of said spring, and a wider bar mounted on the other face and extending inwardly from the edge to beyond the spring, and parts of the coils of the spring abutting against the inside surface of said wider bar.

4. In a metallic reed or comb for textile work having a plurality of spaced dents mounted therein, a coil spring for spacing said dents in the structure having its convolutions extending into the spaces between the dents from one face of the reed but not beyond the other face thereof, a bar mounted on one face adjacent an edge of the structure and extending inwardly from said edge to a projecting portion of said spring, a wider bar mounted on the other face and extending inwardly from the edge to beyond the spring, parts of the coils of the spring abutting against the inside surface of said wider bar, and a rod extending through the coils of the spring in the portions thereof opposite said wider bar.

5. A metallic reed or comb for textile work having a plurality of spaced dents mounted therein, a coil spring for spacing said dents in the structure having its convolutions extending into the spaces between the dents from one face of the reed but not beyond the other face thereof, a bar mounted on one face adjacent an edge of the structure and extending inwardly from said edge to a projecting portion of said spring, a wider bar mounted on the other face and extending inwardly from the edge to beyond the spring, said wider bar having parts of the coils of the spring abutting against the inside surfaces thereof, a rod extending through the coils of the spring in the portions thereof opposite said bar, and solder in the interstices at the ends of the dents and in and around the spring.
